UNITED STATES PATENT OFFICE.

GEORGE BURDICK, OF CLEVELAND, OHIO, ASSIGNOR OF ONE-HALF TO
LOREN PRENTISS, CHARLES M. VORCE, AND SEYMOUR C. PRENTISS,
OF SAME PLACE.

SEWING-MACHINE.

SPECIFICATION forming part of Letters Patent No. 268,458, dated December 5, 1882.

Application filed March 16, 1882. (No model.)

To all whom it may concern:

Be it known that I, GEORGE BURDICK, of Cleveland, in the county of Cuyahoga and State of Ohio, have invented certain new and useful Improvements in Sewing-Machines; and I do hereby declare the following to be a full, clear, and exact description of the invention, such as will enable others skilled in the art to which it pertains to make and use the same.

10 My invention relates to sewing-machines; and it consists in the peculiar construction of the same, as will be hereinafter fully set forth and claimed.

In the drawings, Figure 1 is a view in side elevation of a machine constructed according to my invention. Fig. 2 is a plan view of the underside of the bed-plate, showing the shuttle-driving and feed-operating pitman and lever and the manner of operating the same. Figs. 20 3, 4, 5, 6, 7, 8, 9, 10, 11, 12, and 13 are detached views of some of the parts of my machine, showing their construction more clearly.

A is the bed-plate of my machine. B is the standard, and C is the horizontal arm, which 25 extends from the upper end of the standard B, as is usual in sewing-machines.

My machine is driven by means of power applied to the wheel D, which is detachably secured to the horizontal driving-shaft D' by the 30 following devices: A collar, D², is securely attached to said shaft D'. This collar D² in turn is provided with a pin, a, which is loosely journaled in the collar, one of its ends extending out and being provided with a head or knob, 35 so as to be grasped by the operator, and the other end engaging, when in operation, with a hole, b, in the wheel D, it being kept in place in said hole b by means of a spring, c. When it is desired to disengage the pin a from the 40 hole b the said pin is pulled outward.

To the collar D² is attached a stud, d, which extends within the bore of the collar and enters the slot e to be moved backward and forward a limited distance. A slot, e', located at right 45 angles to the slot e, connects with the latter, and hence when the pin a is retracted and given a partial rotation the stud will engage the transverse slot e' and retain the pin out of contact with the wheel D, thereby allowing the

latter to revolve freely without revolving the 50 shaft D', this being desirable when the bobbin is being wound.

To cause the pin a to engage with the wheel D, it is only necessary to turn said pin so that the stud d is out of the branch slot e', which 55 allows the end of the pin a to press against the wheel D by means of the spring c, and when the hole b is opposite said pin a the said pin will slip in the said hole and be held there by means of the spring c.

The horizontal shaft D' imparts motion to a vertical shaft, E, by means of miter-gears.

To the lower end of the shaft E is secured a cam, E', which engages with and acts to operate the feed-lever E², giving said lever a 65 longitudinal reciprocating motion. The lever E² is kept in contact with said cam E' by means of a spring, E³.

f is a pivoted bearing, through which the 70 feed-lever E² slides.

F is a bearing-shoulder, constituting an inclined plane formed on a plate or bar pivoted to the under side of the bed-plate A, and made adjustable by means of an arm, F', and thumb-screw g, extending up through a curved slot in 75 the bed-plate A. The function of the inclined plane F is to cause the rounded end h of the lever E² to engage with it (when said lever is being pushed outward by the cam E') and act in connection with the spring E³ to give to the 80 feed-lever E² a transverse reciprocating motion, which is communicated to the feed-bar F².

This motion may be lengthened or shortened by adjusting the inclined plane F, which will 85 act to lengthen or shorten the feed and stitch.

The up-and-down motion of the feed-bar F² is imparted to it by means of an adjustable inclined plane, j, attached to the shuttle-carrier H, (see Fig. 11, wherein it will be observed that a screw extends down from the inclined plane through the plate H, and is provided with nuts for retaining the inclined plane in any desired adjustment.) One end of the inclined plane j is attached to the shuttle-carrier, and the arm V of the inclined plane 95 constitutes a spring, the tendency of which is to keep the incline in its raised position. To the free end of the incline is secured a

screw-threaded stud, V^5 , by means of a pin or rivet, V' , extending through the upper end of the stud and the incline. The stud V^5 extends down through a slot formed in the shuttle-carrier, and its lower end is provided with an adjusting-nut, V^3 , and a jam-nut, V^4 . By loosening the jam-nut the adjusting-nut may be turned so as to adjust the vertical position of the inclined plane, and by turning the jam-nut snugly against the regulating-nut the parts are retained against accidental displacement. The spring E^3 acts to take up any wear that may occur between the devices E' and F and the end of the lever, and thus prevent any looseness or rattling in the parts.

G is a crank, which is also secured to the lower end of the shaft E , below the cam E' . This crank G acts to operate the shuttle lever or pitman G' , which in turn is secured to and operates the shuttle-carrier H , giving to the same a longitudinal reciprocating motion. The shuttle lever or pitman G' is made adjustable, one means of adjusting it being shown in the drawings, Figs. 2 and 12, which consists of a hollow split screw or bolt, G^2 , the head of which is pivoted to the shuttle-carrier H , and a nut, i , having a tapering female screw-thread, which engages with the thread on the bolt G^2 , and, when the end of the pitman G' is entered in the hollow part or socket of the bolt G^2 , acts to clasp said end tightly, and thus, by moving the said end of the pitman G' back or forth in said socket, it may be adjusted and held in the desired position. Any wear occurring between the parts may be thus quickly and easily taken up and the shuttle-carrier timed to the movement of the needle.

I is a crank-wheel securely attached to the forward end of the horizontal shaft D' . The wrist and roller k of this crank-wheel operate to drive the needle-bar by working in a heart-cam, as is usual in machines employing a crank-wheel to drive the needle-bar. This crank-wheel is made cam-shaped, as shown in Fig. 5, which allows it to impart to the bar J a vertical reciprocating motion, which motion is in turn communicated to the take-up K by means of the hook l on the lower end of the bar J . The take-up is kept in contact with said hook l by means of a spiral spring, m , one end of which engages with a small hole in said take-up, the other end being secured in a hole in the head of a pin, m' , said pin m' acting as a pivot or fulcrum for the take-up and as a means for securing it in place. The pin m' is in turn held in place by means of a set-screw, n , and said pin may be turned in either direction to increase or decrease the tension of the spring m , and then secured in the desired position by said set-screw n .

K' is an arm extending out in the rear of the pin m' , and formed in one piece with the take-up K . Said arm reciprocates vertically between a slot formed in a stud, L , which is secured to and extends up from the horizontal arm C . The arm K' is provided with a hole,

o , which, when the arm is at its lowest point, is in a direct line with holes P in the stud L . This allows of the thread being easily passed through the said holes when in this position. The function of this arm K' is to unwind the thread from the spool as fast as needed, thus taking the strain from the needle.

My tension device consists of a piece of metal, M , adjustably secured to the side of the face-plate by means of a set or thumb screw, r , which passes through a slot, s , in the piece M . The upper end of the piece M is made hollow or bored out to a considerable distance, as shown in Fig. 7, and is provided with two disks, t and t' . The faces of these disks, t and t' , which are contiguous, are polished, the edges of the same being slightly chamfered at the point where the two disks meet. I provide a slot, u , cut at a right angle to the bore of the piece M . This allows of the thread being passed between the two disks t and t' from the outside.

The tension of the thread is governed by means of a thumb-screw, N , and spring v , the said spring v resting on the upper disk, t , and the set-screw N pressing on the spring v .

My object in making the piece M adjustable is to allow of the slot u and disks t and t' being moved nearer to or farther from the take-up K , and thus adapt it to different thicknesses of cloth or goods being sewed by the machine.

The manner of threading my machine is as follows: The end of the thread is first passed through one of the holes P in the slotted stud L and then through the hole o in the arm K' , and then out through the other hole P , and from thence through the hook O in the side of the horizontal arm C , then between the disks t and t' and hook y through the hole in take-up K , after which it passes to the needle. When the take-up K is moving in a downward direction the arm K' is moving upward and pulling the thread from the spool, and when the take-up K is moving upward the arm K' is moving down, and the thread is slackened or fed to the take-up K . This operation is repeated at every up and down stroke of the needle-bar and take-up. Thus the only strain on the take-up K is the force required to pull the thread through the tension-disks t and t' and the necessary strain employed in tightening the stitches.

What I claim is—

1. In a sewing-machine, the combination, with the driving-shaft and driving-wheel loosely journaled thereon, of a collar securely attached to the driving-shaft, a pin journaled in said collar and adapted to be reciprocated therein, said pin being provided with an L -shaped slot, a stud secured to the collar and arranged to extend into said slot, and a spring for forcing the pin in one direction, substantially as set forth.

2. In a sewing-machine, the combination, with a cam secured to the lower end of a vertical shaft, of a feed-operating lever and a spring for retaining it in contact with said cam,

- and an adjustable arm provided with an inclined plane, against which engages the rear end of the feed-operating lever, substantially as set forth.
5. In a sewing-machine, the combination, with a feed-operating lever constructed with a lateral extension at its rear end provided with rounded edges, of an adjustable arm provided with an inclined plane, against which engages the lateral extension of the feed-operating lever and imparts lateral movement thereto, substantially as set forth.
10. In a sewing-machine, the combination, with a feed-operating lever and a cam for reciprocating the same, of an arm formed with a shoulder constituting an inclined plane, against which engages the feed-operating lever, and means for adjusting said arm, substantially as set forth.
15. In a sewing-machine, the combination, with a shuttle-operating pitman or lever and a shuttle-carrier, of a split, hollow, and tapering bolt journaled at one end to the shuttle-carrier and receiving the pitman in its other end, and a nut for clamping the hollow bolt upon the end of the pitman, substantially as set forth.
20. In a sewing-machine, the combination, with a take-up provided with a pull-off arm or extension, of stationary thread eyes or passages located on opposite sides of said pull-off, substantially as set forth.
25. In a sewing-machine, the combination, with an independent take-up provided with a pull-off arm or extension, of a tension-regulating device arranged to engage the thread between the pull-off and the take-up, substantially as set forth.
30. In a sewing-machine, the combination, with the combined take-up and pull-off, of the 40 needle-bar J, curved lifting-finger l, and heart-shaped cam I, substantially as set forth.
35. In a sewing-machine, the combination, with a take-up provided with a pull-off arm or extension, of a slotted stud provided with 45 thread-passages, substantially as set forth.
40. In a sewing-machine, the combination, with a take-up provided with a pull-off arm or extension, of a pivotal pin, m', provided with a slotted head, a set-screw, n, to retain the 50 pivotal pin in any desired rotary adjustment, and a spring, m, one end of which is secured to the take-up and its opposite end to the head of the pin m', substantially as set forth.
45. In a sewing-machine, the combination, with the take-up provided with a pull-off arm or extension, of a tension device adjustably secured to the machine and adapted to receive the thread from the pull-off and to be adjusted to regulate the length of thread between the 55 tension device and take-up, substantially as set forth.
50. In a sewing-machine, a tension device consisting in the combination, with the hollow piece M, having a screw-slot, s, and a thread-slot, u, of the disks t' and suitable means for increasing or diminishing the pressure between said disks, substantially as set forth.
55. In testimony whereof I have signed my name to this specification in the presence of two 60 subscribing witnesses.
65. GEORGE BURDICK.
